[57] CLAIM

The ornamental design for a tamper resistant bait tray
or similar article, as shown and described.

DESCRIPTION

FIG. 1 is a side elevational view of a tamper resistant
bait tray, or similar article, showing our new design;
FIG. 2 is a top plan view thereof;
FIG. 3 is a side elevational view thereof taken from the
bottom of FIG. 2;
FIG. 4 is a left side elevational view thereof;
FIG. 5 is a right side elevational view thereof;
FIG. 6 is a bottom plan view thereof;
FIG. 7 is a cross-sectional view thereof, taken along
lines 7—7 of FIG. 2; and
FIG. 8 is a cross-sectional view thereof, taken along
lines 8—8 of FIG. 2.

FIG. 1

FIG. 4

FIG. 2

FIG. 5

FIG. 3

FIG. 6

FIG. 7

FIG. 8
